UNITED STATES PATENT OFFICE.

HUGH E. McLAUGHLIN, QF NEW YORK, N. Y.

ARTIFICIAL-STONE FACING SLAB OR TILE.

1,152,427.

Specification of Letters Patent. Patented Sept. 7, 1915.

Application filed June 25, 1914. Serial No. 847,257.

To all whom it may concern:

Be it known that I, HUGH E. McLAUGHLIN, a citizen of the United States, residing at New York city, in the borough of Bronx, 5 county and State of New York, have invented certain new and useful Improvements in Artificial-Stone Facing Slabs or Tiles; and I do hereby declare the following to be a full, clear, and exact description of the same, 10 reference being had to the accompanying drawings, forming part of this specification, and to the figures and letters of reference marked thereon.

This invention relates to improvements in 15 tiles or slabs formed of concrete or other composition material to form the finish face or surface of brick, cement-block or hollow tile walls, of buildings.

The object of the invention is to provide 20 improved means for securing the facing tiles in place upon the building walls and the invention consists in certain novel details of construction and combinations and arrangement of parts, all as will be now described 25 and the particular features of novelty pointed out in the appended claims.

In the accompanying drawings, wherein is 30 illustrated the preferred embodiment of the invention, Figure 1 is a face view of a slab or tile embodying the present invention with the fastening means in dotted lines. Fig. 2 is a plan view of a tile or slab attached to a wall. Fig. 3 is an end edge view of the tile in place on a wall. Fig. 4 is a similar view 35 showing a different arrangement of the securing means.

Similar letters of reference in the several figures indicate the same parts.

Referring to the drawings A indicates a 40 tile or slab of concrete or other composition, having embedded therein a reinforcement wire B. An intermediate portion b of the reinforcement extends horizontally longitudinally of the slab and has its ends bent 45 upwardly at right angles forming upright portions b', said ends being then bent substantially at right angles to extend out through the inner face of the tile or slab for a suitable distance, as shown at b². These 50 free ends are bent downwardly forming hook-like portions b³, by which the facing tile is held in place upon the wall.

In securing the tiles or slabs in place on the wall the ends b³ are hooked behind or in 55 the openings in the blocks of one course of

the wall with the portion b² resting on the top of the same so as to extend into the joint between the courses as shown clearly in Fig. 3.

The fasteners may project from the rear 60 face of the tile at any points desired or preferred, but when it is desired that the joint between the courses of the building wall and of the facing tiles shall coincide, the fasteners should project from the tile at or near 65 the top, as shown for example, in Fig. 4. In such case it would be undesirable to employ the form of fastener heretofore described, where the portion b' extends straight up from the base portion b, for this would bring 70 the top of the portion b' near the top of the slab or tile and be liable to break through the comparatively thin mass of material above and around the fastener. To overcome this difficulty the construction illustrated in Fig. 4 is adopted in which the portion b⁵ of the reinforcement is inclined at 75 an angle and emerges at approximately the upper inner edge thus leaving a considerable mass of material in the slab over and around 80 the upwardly and rearwardly extending portion of the fastener.

It is to be noted that the ends b³ of the 85 fastener may be hooked in the interior of the wall or be carried through the entire thickness and hooked on the opposite side thereof. When hooked within the thickness of the wall the opposite face may be indicated by dotted lines Z, in Fig. 3.

Having thus described my invention, what 90 I claim as new and desire to secure by Letters Patent is,—

1. A facing tile or slab for the walls of 95 buildings, having a reinforcement and fastener for securing the tile to the face of the wall formed of a single piece of wire, said wire extending horizontally longitudinally of the slab with its ends bent upwardly and then extended outwardly from the rear face of the tile, said rearwardly extended portion forming a support for the slab passing between the blocks of one course of the wall and resting on the top of the same, the free end of the wire being extended downward 100 forming hook-like portions which are hooked behind the blocks.

2. A facing tile or slab for the walls of 105 buildings having a reinforcement and fastener for securing the slab to the face of the wall formed from a single piece of wire,

said wire extending horizontally longitudinally of the slab with its ends bent upwardly and inclined rearwardly of the slab, and then brought out substantially at right angles from the rear face of the slab, forming supports resting on the top of the blocks of one course of the wall, and then bent

downwardly forming hooks which take behind the blocks of one course.

HUGH E. McLAUGHLIN.
